UNITED STATES PATENT OFFICE.

JOHN B. ARCHER, OF WASHINGTON, DISTRICT OF COLUMBIA.

APPARATUS FOR THE MANUFACTURE OF GAS.

SPECIFICATION forming part of Letters Patent No. 501,130, dated July 11, 1893.

Application filed June 8, 1892. Serial No. 436,025. (No model.)

To all whom it may concern:

Be it known that I, JOHN B. ARCHER, a citizen of the United States, residing at Washington, in the District of Columbia, have invented certain new and useful Improvements 5 in Apparatus for the Manufacture of Gas; and I do hereby declare the following to be a full, clear, and exact description of the invention, such as will enable others skilled in 10 the art to which it appertains to make and use the same.

My invention consists in placing in a furnace, the interior of which is divided into a combustion chamber and a heating chamber 15 on each side thereof, by means of tiling, a horizontal fixer which is mounted within the said furnace near the top thereof and above the converging upper ends of the tiling, while horizontal steam super-heating pipes are 20 placed within the fire chamber, and horizontal retorts, into which oil is injected by steam from the said pipes, are contained in the said heating chambers, the said retorts discharging into the said fixer, whereby the vaporized 25 products of the steam and oil which have been decomposed in the retorts will be combined to form a fixed gas, and it also consists in a combination, construction and arrangement of the several parts of which it is composed, as will be hereinafter more fully described and claimed.

Referring to the accompanying drawings in which corresponding parts are designated by similar letters of reference Figure 1 is a central vertical transverse section of a gas producer constructed according to this invention. 35 Fig. 2 is a horizontal section taken on lines *v v* of Fig. 1.

The furnace structure consists of a base *A* 40 from which spring the elliptical or curved walls *A'* which form the sides and top of the structure, a suitable longitudinal depression being formed in the center of the base, the said depression being horizontally divided by 45 the grate bars *a⁸* into the ash pit *a* and the fire or combustion chamber *a'*, the tops of the side walls of the depression being beveled as *a⁶* forming a narrow longitudinal ledge *a⁸* on top of the base *A* at the inside of each side 50 wall *A'*. Front and rear walls *A²A³*, respectively, are provided, inclosing the front and

rear of the furnace structure, the said front wall having fire and ash doors therein. From the top of each ledge *a⁸*, curved tiling *A⁴* substantially eccentric to the side walls *A'* rise, 55 the upper end of the tiling converging toward each other and extending outwardly forming wing-walls *a¹⁴* which are concentric to horizontal fixer, to be hereinafter described, the said side walls *A'* and tiling *A⁴* forming on 60 each side of the structure a heating chamber *a¹²*, each of the said chambers having its upper end communicating with the fire chamber between them, and its lower end with a suitable stack (not shown) by means 65 of the down take *a¹³* formed in the base *A*. A series of return pipes *B* is arranged on each side of the fire chamber inclosed by the said tiling, the rear end of the upper pipe of each series being connected to a suitable steam 70 supply by the pipe *E*, the forward ends of the lower pipe of each the said series entering suitable injectors *F* located at the forward end of the lower retort of each of the series of horizontal retorts *C*, which are contained in 75 the heating chambers, either concentric to the walls thereof or the alternate retorts may be placed near the opposite walls, the upper retort of each series being placed near the outer walls beyond the ends of the wing walls, 80 whereby the heated products of combustion arising from the combustion chamber (where they have heated the steam superheating pipes *B*) will on their downward passage through the heating chambers *a¹²* be deflected from retort to retort imparting all of 85 their heat thereto.

Any preferred means of connecting the several retorts of each series together may be used, although I prefer to use return boxes *L* 90 of the character described in Letters Patent No. 433,926, issued to me on the 5th day of August, 1890, which may be built into the end walls of the furnace, and it will be also obvious that similar return boxes may be 95 used for connecting together the several superheating pipes of each series.

A horizontal fixer *D'* is supported above the center of the combustion chamber and between the wing walls upon the upper edges 100 of the tiling, the said fixer having shoulders formed thereon, which are built into the

walls A' of the structure, the said shoulders in this way serving as a key-stone of the side walls.

The upper retort C of each of the series of 5 retorts is connected with the fixer, which, in case, it is desired to make different grades of gas in the same producer, is divided into a plurality of compartments by a transverse diaphragm d⁴, each of the said series of retorts being connected with one of the said compartments by means of the pipe D², while the gas is withdrawn from each compartment by a separate service pipe I² which enters the said compartment, it being connected with the dome d², which is provided with the movable cover d³, by which access may be had to the interior of the fixer. An oil pipe I' is connected with each of the said injectors F. It will thus be seen that the steam in passing 15 through the pipes B will be superheated, and will pass into the injector with a velocity due to its expansion, and will carry with it a portion of the oil from the pipes I', which oil will be atomized, and will, in the heated retort C, become converted into a vapor, which will be mechanically mixed with the superheated steam, together with which it will enter the highly heated fixer D', where the hydrogen of the steam will unite with a portion of the 20 carbon of the oil, forming a hydrocarbon gas, which together with the gas formed by the partial decomposition of the vaporized oil will flow into the dome d² from which the fixed gas may be withdrawn for the purpose of combustion.

It will be noted that as the superheating pipes are contained in fire chamber, directly over the fire, that they may be subjected to an intense heat, thoroughly superheating 25 the steam, and that as the retorts C are contained in the heating chambers and are heated solely by the products of combustion which have already imparted a part of their warmth to the fixer that the danger of over-heating 30 the retorts and thus forming a deposit of carbon therein is greatly lessened, and that the fixer itself, situated between the wing walls of the tiling is in a position to be readily raised to a high temperature.

Having thus described my invention, what I claim is—

1. The combination with a furnace having curved walls and top, of tiling located within the said furnace on each side thereof and being concentric to the corresponding walls, forming a combustion chamber and a heating chamber on each side of the combustion chamber and communicating therewith at the top; a series of steam superheating pipes located within the said combustion chamber on each side thereof and concentric to the corresponding tiling, a series of horizontal retorts located in each of the said heating chambers, an oil supply pipe connected with 55 each of the said series of retorts, a horizontal fixer contained within the said furnace at the

top of the combustion chamber and between the converging upper ends of the tiling; and downtakes communicating with the lower ends of each of the said heating chambers, 70 the said series of retorts having their lower ends communicating with the superheating pipes and their upper ends communicating with the fixer, substantially as described.

2. The combination with a furnace provided 75 with side walls and top, of tiling located within the said structure on each side thereof and concentric to the corresponding side walls, forming a central combustion chamber and a heating chamber on each side thereof, communicating therewith at the top, the tops of the said tiling being bent outwardly, forming wing-walls; a series of steam superheating pipes located within the said combustion chamber on each side thereof, concentric to 80 the corresponding tiling; a series of horizontal retorts located in each of the said heating chambers; an oil supply pipe connected with each of the said series of retorts, the alternate retorts of each series being located upon the 85 opposite sides of the chambers containing them, a horizontal fixer contained in the said furnace at the top of the combustion chamber and between the wing-walls upon the said tiling, and downtakes communicating with the 90 lower ends of the said heating chambers, each of the said series of retorts having their opposite ends communicating with the said superheating pipes and fixer, respectively, substantially as described.

3. The combination with a furnace, of tiling located within the said structure on each side thereof and having converging upper ends, forming a central combustion chamber and a heating chamber on each side thereof, 105 communicating therewith at the top, the tops of the said tiling being bent outwardly, forming wing walls; a series of steam superheating pipes located within the said combustion chamber on each side thereof, concentric to 110 the corresponding tiling, a series of horizontal retorts located in each of the said combustion chambers; an oil supply pipe connected with the said retorts, a horizontal fixer contained in the said furnace at the top of the 115 combustion chamber and between the wing walls upon the tiling, and downtakes communicating with the lower ends of the said heating chambers, substantially as described.

4. The combination with a furnace having 120 arched side walls and top, of a horizontal fixer having shoulders thereon built into and forming the key of the said arched walls; steam superheating pipes and retorts contained in the said furnace, the said superheating pipes 125 being connected to one end of the retorts, and the opposite end of the said retorts being connected with the said fixer, and an oil supply pipe connected with the said retorts, substantially as described.

5. The combination in a furnace of two series of superheating pipes and retorts con-

tained therein, each of the said series of super-heating pipes being connected with the corresponding series of retorts, a fixer contained in the said furnace and having its interior divided into two compartments by a diaphragm, each of which compartments is connected with one of said series of retorts, an oil supply pipe connected with each of the said series of retorts, and an eduction pipe

leading from each of the compartments of the fixer, substantially as described.

In testimony whereof I affix my signature in presence of two witnesses.
